UNITED STATES PATENT OFFICE.

LILLY SCHMIDT, OF KLOTZSCHE, NEAR DRESDEN, GERMANY.

GUIDE FOR VIOLIN BOWS.

Application filed January 22, 1925. Serial No. 4,023.

To all whom it may concern:

Be it known that I, LILLY SCHMIDT, a citizen of the German Republic, residing at Klotzsche, near Dresden, Goethestrasse 10, 5 Germany, have invented certain new and useful improvements in Guides for Violin Bows, of which the following is a specification.

The object of the present invention is a 10 guide for violin bows. When starting to play a violin, viola or cello, beginners find it usually very difficult to learn how to draw a straight bow. In most cases the bow will be drawn so that it often passes beyond the 15 bridge and over the strings of the fret-board, while good playing requires that the bow does not only keep within the limits set by bridge and fret-board but is drawn perfectly straight, i. e. in a direction running 20 perpendicular to that of the strings, and experiments made with the object of the present invention have shown that persons unskilled in the art of playing string instruments can easily learn how to draw a straight 25 bow. I am aware of the fact that guides for violin bows have been invented consisting of a frame attached to the fret-board for the purpose of preventing the bow from passing over the strings beyond the fret-board, but the present invention aims chiefly 30 at preventing the bow from slipping over the bridge. This is accomplished by placing a guard over the lower end of the tail-piece and attaching it by means of a clasp. 35 This guard is suspended over the bridge without touching it. If, in addition, one of the known types of frames is pushed over the fret-board, the player will be compelled to keep the bow within the space marked by 40 the guard and frame, and the bow will be drawn perfectly straight whenever it comes in contact with one or the other of the two devices mentioned.

One form of the invention is illustrated in 45 the accompanying drawing, in which Figure 1 is a side view of the device attached to a violin; Fig. 2, a view of the device as seen from above; Fig. 3, a sectional view on the line *a*—*b* from *c*, Fig. 1; Fig. 4, a sectional view on the line *b*—*d* seen from *e*, Fig. 2; and Fig. 5, a view in perspective of the guard to be secured above the tail-piece.

1 is the violin with the bridge 2, the tail-piece 3 and the fret-board 4. 5 are the 50 strings arranged in the usual manner. Over the fret-board 4 is pushed a frame 6 having

a U-shaped cross section, and the inner edges 7 of the frame 6 hug the fret-board 4 so as to leave a free passage for the strings 8. Spring action due to the resiliency of the 60 material of which the frame is made keeps the latter above the finger board. 9 is the guard which is attached to the tail-piece by means of a clasp 10 and a press button 11 in such a manner that the only point of 65 connection between the guard 9 and the tail-piece is formed by the fastening clasp 10, while the stiffened front part 12 is kept in suspended position above the strings 5 and extends slightly across the bridge. The 70 clasp 10 is attached permanently to guard 9 so that it is integral with the guard. Its rear end, which firmly grips and surrounds the tail-piece 3, prevents the guard from slipping out of place. Being very stiff and 75 of such a length as to protrude over and beyond the bridge the guard is kept in suspended position above the bridge and strings.

Owing to this arrangement the strings are 80 not touched either by the frame 6 or the guard 9, and the playing is not interfered with, while, on the other hand, straight drawing of the bow is ensured by arranging guard 9 on one side and frame 6 on the 85 other. The player is compelled to draw a straight bow as he cannot draw the bow beyond the bridge 2 or play on the strings over the fret-board 4.

The working method of the device will be 90 readily understood from what has been said above. The guard 9 is preferably made from celluloid or leather but any other suitable stiff material may be employed.

The guide can be used in connection with 95 all sorts of string instruments by adapting it to the size of the particular instrument to which it is attached.

I claim:—

A guide for violin bows consisting of a 100 frame attached to the finger-board and of a guard possessing great stiffness and being of such a length as to protrude above and beyond the bridge: the said guard being placed over the lower end of the tail-piece 105 and secured by means of a clasp so as to be kept in suspended position above the bridge and strings.

In testimony whereof I have affixed my signature.

LILLY SCHMIDT.
